DESIGN FOR A CIGARETTE HOLDER

Gloria Goldman, Los Angeles, Calif.

Application November 20, 1945, Serial No. 123,934

Term of patent 3½ years

(Cl. D85—8)

To all whom it may concern:

Be it known that I, Gloria Goldman, a citizen of the United States of America, residing in Los Angeles, county of Los Angeles, and State of California, have invented a new, original, and ornamental Design for a Cigarette Holder, of which the following is a specification, reference being had to the accompanying drawing, forming part thereof, wherein

The rear of the cigarette holder is substantially the same in appearance as the front.

I claim:

The ornamental design for a cigarette holder, substantially as shown and described.

GLORIA GOLDMAN.
